UNITED STATES PATENT OFFICE.

EDWARD J. DACEY AND ALBERT A. GORDON, OF WORCESTER, MASSACHUSETTS, AS
SIGNORS TO CROMPTON AND KNOWLES LOOM WORKS, OF WORCESTER, MASSACHU-
SETTS, A CORPORATION OF MASSACHUSETTS.

REVERSING SHIPPING MECHANISM FOR LOOMS.

Application filed September 29, 1925. Serial No. 59,414.

To all whom it may concern:

Be it known that we, EDWARD J. DACEY and ALBERT A. GORDON, citizens of the United States, both residing at Worcester, 5 in the county of Worcester and State of Massachusetts, have invented a new and useful Reversing Shipping Mechanism for Looms, of which the following is a specification.

10 This invention relates to driving mechanism for looms and more particularly to an improved reversing means therefor.

In certain classes of looms, such as those for weaving Axminster and Wilton carpets, 15 it is occasionally desirable to reverse the direction of the loom so that a miss-pick, or other defect, may be corrected. It is desirable, however, to permit the loom to run in a reverse direction only so long 20 as the weaver is in attendance. Accordingly, it is the principal object of our invention to provide the shipper mechanism with devices which prevent the shipper handle from being held mechanically in running 25 position while the loom is running in a reverse direction.

The usual shipping mechanism of the 30 types of looms referred to embraces a bracket extending laterally from the loom-side and having a longitudinal slot therein at the outer end of which is located a notch. Some portion of the shipper handle ordinarily occupies the notch while the loom 35 is running in a forward or normal direction and is held in the notch so as not to require constant attention by the weaver. It is a more particular object of our invention to provide a lever pivoted to the bracket and having a boss which normally 40 is held out of contact with the shipper handle but which, when the motor is reversed, is moved to position to prevent the shipper handle from entering the notch.

45 With these and other objects in view which will appear as the description proceeds, the invention resides in the combination and arrangement of parts hereinafter described and set forth in the claims.

50 In the accompanying drawings, wherein we have shown a convenient embodiment of our invention,

Fig. 1 is a front elevation of part of the

right hand end of a loom having our invention applied thereto,

55 Fig. 2 is a vertical section taken on line 2-2 of Fig. 1.

Fig. 3 is an enlarged horizontal section taken on line 3-3 of Fig. 1, showing the parts in normal running position,

60 Fig. 4 is a view similar to Fig. 3, but showing the parts in position for reversing the motor, and

Fig. 5 is a perspective detail view of the 65 reversing lever.

Referring to the drawings, it will be seen that we have provided a loomside 10 from the right hand end of which extends an end frame 11, which, in Axminster looms, serves to support the needle motion and in Wilton looms supports the wire motion. A shipper lever 12 is pivoted as at 13 to some fixed part of the structure and is formed with a hand hold 14 by means of which the same may be manipulated by 70 the weaver. A cross shaft 15 is suitably journaled in the end frame 11 and has secured to the forward end thereof an arm 16 provided with a pin 17 which moves in a slot 18 formed in the shipper handle 12. 75 The rear end of the shaft 15 has secured thereto a forked arm 19 having operative contact with a sliding clutch member 20 keyed to the bottom shaft 21 of the loom. Said clutch member 20 is movable to co- 80 operate with a second clutch member 22 fastened to gear 23 which is loosely mounted on bottom shaft 21. Pinion 24 meshes with the gear 23 and is driven by 85 motor 25 to drive the shaft 21 when the clutch members are interengaged. The 90 matter thus far described is of common construction and forms no part of our present invention.

In carrying out our improvements we provide a switch box 30 secured in any convenient manner to the end frame 11 and provided with an arm 31 by means of which a switch located therein may be thrown to reverse the direction of current leading to 100 the motor 25 through the conductor 32. As any convenient form of reversing switch may be employed we do not deem it necessary to show the same in detail, it being sufficient for our present purposes to state 105 that when the arm 31 is in the full line posi-

tion shown in Fig. 1 the motor drives the loom in a forward direction and when moved to the dotted line position the motor will be reversed. A bracket 33 is secured 5 to the loomside and has formed therein a slot 34, the outer end of which is provided with a notch 35 proportioned to receive the shipper handle 12 when the latter is in driving position. Said bracket is provided 10 with an upstanding boss 36 in which is secured a stud 37 forming a pivot for a reversing lever 38. Said lever is provided at one end thereof with a weighted handle 39 and at the other end thereof has pivotal 15 connection with rod head 40 carried by a rod 41 connected to the arm 31. Said reversing lever is also provided with a lug 43 extending rearwardly and having the rear face thereof in substantial alignment 20 with the forward wall of slot 34.

Under normal running conditions the parts are in the position shown in Fig. 3 with the shipper handle 12 held in the notch 35 so that the loom continues to run without 25 attention on the part of the weaver. When, for any reason, it is desired to reverse the direction in which the motor 25 rotates, the shipper handle will be thrown from the full line position to the dotted line position 30 shown in Fig. 3 to stop the loom, after which the reversing lever 38 will be thrown from the position shown in Fig. 3 to the position shown in Figs. 1 and 4. By referring to Fig. 4 it will be seen that the lug 35 35 covers the notch 35 so that the shipper handle 12 is not permitted to enter said notch and must be held in the driving position by the weaver. In this way it is impossible for the weaver to leave the motor 40 running in reverse direction without continued attention. The lug 43 is so proportioned that if an attempt were made to throw the lever 38 while the shipper lever occupied the notch said lever would stop 45 the lug and prevent sufficient motion of the lever 38 to throw the switch to reverse position.

It is to be understood that shipper lever 12 is held in the notch 35 by its own resilience, being moved by the weaver against its 50 resilience from the dotted to the full line position shown in Fig. 2 when the loom is to be stopped. A spring 44 serves to move the shipper lever from the dotted to the full line position shown in Fig. 1 when the said lever is removed from notch 35.

From the foregoing it will be seen that we have provided a very simple means for requiring constant attention on the part of 60 the weaver when the loom is being run in the reverse direction, and that it is impossible for the weaver to abandon control of the shipping mechanism without automatically stopping the loom. Also, the shipper lever when in notch 35 will prevent sufficient 65

movement of the lever 38 to effect reversal of the loom, the parts being so arranged that it is impossible for the shipper lever to be held mechanically in running position when the loom is reversed. 70

Having thus described our invention it will be apparent that changes and modifications may be made therein by those skilled in the art without departing from the spirit and scope of the invention, and we do not wish to be limited to the details herein disclosed but what we claim is: 75

1. In loom controlling mechanism, driving mechanism, a shipper lever to connect the loom with the driving mechanism in 80 normal running position when the mechanism is driving the loom in forward direction, and means to reverse the driving mechanism and also prevent said shipper handle from moving to normal driving 85 position.

2. In loom controlling mechanism, driving mechanism for the loom, reversing means for the driving mechanism, a shipper lever normally held in driving position, 90 and a controller for the reversing means to engage the shipper handle to prevent the same from moving to normal driving position when the loom is running reversed. 95

3. In loom controlling mechanism, driving mechanism for the loom, reversing means for the driving mechanism, a shipper lever held in normal running position when the loom is being driven forwardly, 100 and a controller for the reversing mechanism including means to prevent the shipper lever from moving to normal running position when the driving mechanism is reversed. 105

4. In controlling mechanism for looms, driving mechanism for the loom, reversing means for the driving mechanism, a shipper lever to connect the loom with the driving mechanism, a bracket having a slot 110 therein to guide the shipper handle and a notch opening into the slot to hold the shipper handle when the loom is in normal running position, and control devices for the reversing means including a member movable into operative relationship with respect to the shipper handle when the driving mechanism is reversed to prevent said shipper handle from moving into the notch. 115

5. In driving mechanism for looms, a shipper lever, a bracket having a slot therein to guide the shipper lever and a notch formed therein communicating with the slot and adapted to receive the shipper lever when the loom is in normal running position, and means mounted on the bracket and movable to overlie the notch to prevent the shipper lever from entering said notch when so desired by the operator. 125 130

6. In control mechanism for looms, driving mechanism for the loom, reversing means for the driving mechanism, a shipper lever for the driving mechanism, a bracket extending from the loom and having a slot therein to guide the shipper handle and a notch communicating with the slot to receive said shipper handle when the loom is being driven in normal forward direction, and a control lever pivoted to the bracket and operatively connected to the reversing means, said control lever having a portion to cover the notch and prevent the shipper handle from entering the same when the driving mechanism is reversed.

7. In control means for loom driving mechanism, reversing means for the driving mechanism, a shipper lever to connect the loom with the driving mechanism, a bracket having a slot therein to guide the shipper lever and a notch communicating with the slot to receive the shipper lever when the loom is running in a normal forward direction, a control lever pivoted to the bracket and operatively connected to the reverse means, and a lug formed on said control lever and movable when the

said means is moved to the reverse position to overlie the notch and prevent the shipper handle from entering the same.

30

8. A control lever for the reversing mechanism of a loom having a bracket provided with a slot to receive the shipper lever and a notch to hold said lever in normal running position, said control lever having a portion to lie over the notch when the loom is reversed and hold the shipper handle out of said notch.

35

9. In a control mechanism for looms, driving mechanism, reversing means for the mechanism, a shipper lever for the driving mechanism, a bracket having a guide slot for the lever and a notch to receive said lever when the loom is running normally, a control lever for the reversing means, and a lug on said control lever positioned to engage the shipper lever when the latter is in the said notch and prevent movement of the control lever to reverse the loom.

40

In testimony whereof we have hereunto affixed our signatures.

45

EDWARD J. DACEY.
ALBERT A. GORDON.
